UNITED STATES PATENT OFFICE

WALTER F. DEHUFF, OF GLEN ROCK, PENNSYLVANIA

GREASING BRUSH

Application filed December 31, 1930. Serial No. 505,870.

This invention relates to brushes; and more particularly, to a brush adapted to be used in connection with a pan greasing machine commonly used in connection with greasing pans in the baking industry.

The prime object is to prevent grease that is normally fed through the hollow stem or sleeve onto the brush from leaking onto the machine during the feeding process. As usually used, the grease is melted and fed into a grease pump from which it is forced through a hollow sleeve onto a brush head. A foot pump is usually utilized, as a continuous feed is not necessary. Under these conditions due to the fact that the brush head is usually made of wood and a close fit cannot be obtained between the metal sleeve and the wooden brush head, the grease has a tendency to flow back along the outside of the sleeve onto the machinery, creating a very unsightly and undesirable condition, at the same time providing inadequate lubrication for the brush head.

In my invention, this condition is impossible due to my providing seals in the brush to overcome these objections.

Another object is to provide a stronger and more durable construction between the brush head portion and the grease feeding mechanism.

Other objects will be disclosed in the specification and claims forming a part of this application.

In the drawing:

Figure 1 is a side elevation of the greasing apparatus in connection with a pan, a portion of the pan being broken away;

Figure 2 is a side elevation of the greasing apparatus, with a vertical section taken through the brush head; and

Figure 3 is a bottom plan of the brush portion.

Referring to the drawing in which like parts are designated by similar numerals:

Numeral 4 designates a dough pan of the usual construction which must be greased before receiving the dough. Numeral 5 designates a wooden brush head having a bore 6 extending therethrough, the upper end 7 of the bore 6 being of smaller diameter than the

lower end 8. Bristles 9 are secured in the outer periphery 10 of the head 5 by means of staples 11 or other suitable means. A metal tube 12 having its upper end 13 conforming to the upper end 7 of the bore 6 is forced into the bore 6. A shoulder 14 is formed on the tube 12 and adapted to fit closely against a similar shoulder 15 formed in the bore 6 due to the lower portion of the bore being cut away.

The upper end of the tube 12 is swedged outwardly to hold the same firmly in position. A groove 16 is formed in the bottom face 17 of the brush head 5 and extends into the bore 6. A hollow spindle 18, having a collar 19 secured thereto and keys 20 formed on one face adapted to engage the groove 16, causes the brush head 5 to rotate with the spindle 18. The collar 19 is spaced a sufficient distance from the end of the spindle 18 so that a close fit can always be maintained between the end of the spindle 18 and the shoulder 14 and yet enable the keys 20 to engage the groove 16. The spindle 18 is supported in bearings 21 and 22 in any suitable manner, and has a gear 23 which may be attached to any well known drive means. A ball bearing 24 is positioned on the spindle 18 directly above the bearing 21.

Under this construction a grease seal is formed at 25 by the swedging of the sleeve 12, which at the same time draws the shoulder 14 tightly against the shoulder 15 forming a second grease seal 26. The lower portion of the tube 12 forms a close sliding fit with the spindle 18 and the end of the spindle 18 fits tightly against the underside of the shoulder 14. Since both the tube 12 and spindle 18 are of metal, the same may be machined to a very close fit which is not true where metal is contacting with wood, which is the case under the old construction.

Under my construction, a film of grease will accumulate from the shoulder 14 to the lower end of the tube 12 forming a seal, the grease forming the film which would not be true where the metal was contacting with the wood since the wood would have a tendency to absorb the grease.

As actually used, the grease will be first

melted and forced under pressure by means of a hand pump through the spindle 18 through the tube 12 until it reaches the brush bristles 9. It is evident that it is literally impossible for this grease to work back around the tube 12 and spindle 18 due to the seals described. A much superior construction is obtained by having the groove 16 in the lower face of the brush head 5 instead of having this feature on the interior of the bore 6, as a more positive locking is obtained and the same may more easily be formed in the head 5.

It is obvious that the subject matter of my invention may be utilized in ways other than illustrated in my drawings, and I do not limit myself to this structure, but include means of accomplishing the same result which may fall within the scope of the claims appended hereto.

What I claim is:

1. Pressure grease brush for greasing pans and the like comprising a brush head and a conduit for supplying the grease thereto, said conduit being divided in said head, the upper part being a tube fixed to said head, and the lower part being a spindle for rotating said brush head, said tube telescoping with sliding sealing fit into said spindle.

2. Pressure grease brush for greasing pans and the like comprising a brush head and a conduit for supplying grease thereto, said conduit comprising a tube fixedly fitted in sealing contact with the walls of a bore in the brush head, and a spindle extending into a counter-bore in said head, said tube telescoping with sliding sealing fit into said spindle.

3. Pressure grease brush for greasing pans and the like comprising a brush head having a bore extending therethrough and an enlarged coaxial counter-bore forming a shoulder, a tube positioned in said bore having a collar adapted to seat on said shoulder and form a seal, a spindle extending into said counter-bore, in which said tube telescopes with sliding sealing fit, and interdigitating means on said spindle and said head for causing the two to rotate together, said top and said spindle forming a conduit for feeding grease under pressure to the brush head.

4. Pressure grease brush for greasing pans and the like comprising a brush head having a bore extending therethrough and an enlarged coaxial counter-bore forming a shoulder, a tube positioned in said bore and having a collar adapted to fit on said shoulder and form a seal, the top portion of said tube being swedged outwardly into intimate contact with the brush head to form a seal, a spindle extending into said counter-bore, in which said tube telescopes with sliding sealing fit, and interdigitating means on said spindle and head for causing the two to rotate together, said tube and said spindle forming

a conduit for feeding grease under pressure to said brush head.

5. Pressure grease brush for greasing pans and the like comprising a brush head having a bore extending therethrough and an enlarged coaxial counter-bore forming a shoulder, a tube positioned in said bore and having a collar adapted to seat on said shoulder and form a seal, a spindle extending into said counter-bore, in which said tube telescopes with sliding sealing fit, said spindle having a key formed thereon and adapted to fit in a groove formed in said head to cause the two to rotate together, said tube and spindle being adapted to feed grease under pressure to said brush head.

In testimony whereof I affix my signature.
